UNITED STATES PATENT OFFICE

ALFRED P. RUDOLPH, OF DENVER, COLORADO

MASSAGE DEVICE

Application filed January 18, 1930. Serial No. 421,719.

This invention relates to improvements in hand operated vacuum massage devices and has reference more particularly to an improvement in the construction of the device described and claimed in U. S. Letters Patent No. 1,730,535, granted to me on October 8, 1929.

It is often necessary to subject the skin of the face and other parts of the body to a gentle suction while it is being massaged and for this purpose a hand operated device like the one that forms the subject of this invention has been found very useful.

It is the object of this invention to produce a device of the type referred to which shall be of neat and substantial construction and which shall be provided with means for adjusting the intensity of the vacuum and which shall also be provided with valves for retaining the vacuum in the applicator during the return stroke of the piston.

The above and other objects that may appear as the description proceeds are attained by means of a construction and an arrangement of parts that will now be described in detail, reference for this purpose being had to the accompanying drawings in which the preferred embodiment of my invention has been illustrated, and in which:

Fig. 1 is a longitudinal section of the improved vacuum massage device;

Fig. 2 is a section taken on line 2—2, Fig. 1, and shows the construction of the piston operating means;

Fig. 3 is a section taken on line 3—3, Fig. 1, a portion of the valve being broken away to better disclose the construction;

Fig. 4 is a section showing a modified form of applicator;

Fig. 5 is a section through one end of the device showing a slightly modified form of construction; and

Fig. 6 shows another form of applicator that is adapted for special uses.

In the drawings reference numeral 1 represents an elongated tubular member that forms the cylinder of the device. One end of this member is closed by an end closure 2 that is preferably soldered or brazed in position. This end closure has an inwardly ex-

tending cylindrical hub 3 that is provided with a threaded opening 4 with which the adjusting screw 5 is operatively associated. Member 1 is provided on one side with an elongated slot 6 and at the other end with a lug 7. The open end of member 1 has a portion of its outer surface threaded as indicated at 8 and a cap 9 is operatively associated with the threaded portion in the manner shown in Fig. 1. Cap 9 is provided with a central opening 10 through which the stem 11 of the applicator 12 extends. The open end of member 1 is closed by means of a rubber plug 13 that has a central opening through which the stem 11 extends. This plug is of a somewhat larger diameter than the inside of the tubular member and is held in place by the action of the cap 9. The stem 11 preferably extends entirely through the plug and terminates flush with the inner surface thereof, but this is not an essential feature of the construction. Secured to the inner end of the plug is a flexible flap 14 that is held in place by a pin 15. When this flap is in the full line position shown in Fig. 3, it serves as a valve member that permits air to move inwardly through the applicator and into the cylinder but which prevents air from moving in the opposite direction. When this valve is in operative position, it helps to retain the vacuum in the applicator during the return stroke of the piston. When the valve is not desired, it can be moved to dotted line position Fig. 3.

Located within the tubular member is a piston which comprises two washers 16 and 17 between which is located a leather cup 18. The assembly of washers and cup is clamped between the nuts 19 and 20 that are threadedly secured to the piston rod 21. Secured to the other end of the piston rod is a guide 22. This guide is preferably provided with a depression at its outer end and within this depression is located one end of a compression spring 23 whose other end rests against the inner surface of the end closure 2. Spring 23 is under compression and tends to move the piston away from the end closure and to retain the parts in the position shown in Fig. 1. Screw 5 serves as a stop that limits

the outward movement of the piston and the guide and since this screw can be adjusted the length of the stroke can also be adjusted in a manner and for a purpose that will hereinafter appear. Secured to the guide 22 is a lug 24. This lug extends outwardly through the slot 6 and the inward movement of the piston and the guide is limited by the engagement of lug 24 with the inner end of slot 6.

10 For the purpose of reciprocating the piston an operating means comprising two toggle levers 25 has been provided. Levers 25 are preferably made exactly alike and one of them is pivotally attached to the lug 7 by means of a pin 26, while the other is pivotally connected with lug 24 by means of a pivot pin 27. The ends of the two levers are connected by a pivot pin 28 and this also holds a plate 29 in place. The plate 29 is provided on opposite sides with lugs 30 that extend downwardly over the sides of the levers. The upper surface of plate 29 is concave and serves as a rest for the finger by means of which the device is operated. When the parts are in normal position, they occupy the full line position shown in Fig. 1, but when pressure is applied to plate 29, the toggle is straightened into the position shown by dotted lines, and this moves the piston and guide towards the right until the outer surface of the guide comes in contact with the inner surface of the adjustable stop 5. A felt washer 31 is located between the plug 13 and the piston and this washer serves as a filter and prevents liquids, oils or other foreign matter from coming in contact with the piston. If this filter becomes soiled it can readily be removed and replaced by a clean felt washer. The leather cup 18 is made from flexible leather and permits air to move from the front to the rear thereof, but prevents air from flowing in the opposite direction, and therefore when the piston is moved towards the right, it sucks air from the applicator into the cylinder and when the piston is permitted to move towards the left, the air which is prevented from returning to the applicator by the action of valve member 14 flows by the piston towards the left hand side thereof.

50 Instead of employing the felt washer 31, the applicator can be constructed in the manner shown in Fig. 4, from which it will be seen that the applicator has been provided with an enlarged portion 32 that is adapted to receive a plug of absorbent cotton 33. This cotton serves as a filter and can readily be removed and replaced by a clean plug whenever this becomes necessary.

60 The applicator shown in Figs. 1 and 4 is provided with a belled outer end which has considerable size and which is intended for use as a massage device. When this device is to be used for removing blackheads or for removing pus from pimples, or any similar use, an applicator like that shown in Fig. 6

is employed. This applicator differs from the other in this, that the outer end is of much smaller diameter and therefore when it is applied it limits the action of the vacuum to a small area and this has been found to be especially well adapted for removing pus and blackheads.

70 In my patent above identified, I have shown the inner end of the plug provided with a rubber bag 34 and in Fig. 5 I have shown this bag applied to my present device. By interposing a felt washer 31 between the rubber bag and the piston, the bag will not become entangled with the piston as it might if washer 31 were not employed.

75 From the above description it will be apparent that I have produced an improved massage device of a simple and substantial construction and which is provided with means for regulating the intensity of the 80 vacuum to any extent required. By providing a guide 22 for the end of the piston rod, the necessity of having the piston rod extend through the end of the device in the manner shown in my patent, has been obviated. The 85 use of a guide also makes it possible to provide an adjustable stop to limit the stroke of the piston.

90 Having described the invention what is claimed as new is:

95 1. A hand operated vacuum massage device comprising, in combination, a cylinder formed from a tubular member having one end closed and the other open, a piston slidably mounted in the cylinder, a guide member secured to the piston and spaced from the latter, said guide member engaging the wall of the cylinder, a spring located between the guide member and the closed end, said spring being under compression and exerting a force tending to move the piston towards the open end, the tubular member having a slot, a pin secured to the guide member and extending through the slot, means comprising a toggle having one end attached to the pin and the other end connected with the tubular member for moving the piston against the force exerted by the spring and an applicator secured in the open end of the tubular member.

100 110 115 120 125 130 2. A hand operated vacuum massage device comprising, in combination, a cylinder formed from a tubular member having one end closed and the other open, a piston slidably mounted in the cylinder, a guide member secured to the piston and spaced from the latter, said guide member engaging the wall of the cylinder, a spring located between the guide member and the closed end, said spring being under compression and exerting a force tending to move the piston towards the open end, the tubular member having a slot, a pin secured to the guide member and extending through the slot, means comprising a toggle having one end attached to the

pin and the other end connected with the tubular member for moving the piston against the force exerted by the spring, an applicator secured in the open end of the tubular member and a check valve associated with the applicator, said valve permitting air to flow into the cylinder but not out therefrom.

In testimony whereof I affix my signature.
